Term of patent 14 years

(Cl. D81—1)

FIG. 1.

FIG. 2.

FIG. 3.

FIG. 4.

Figure 1 is an elevational view of a portable cable vulcanizer showing our new design;

Figure 2 is a similar view looking from right to left in Figure 1;

Figure 3 is a fragmentary enlarged view in elevation showing the head of the vulcanizer with the molding jaws in a partially open position; and

Figure 4 is a head end view of the vulcanizer.

The dominant features of the design reside in the portions shown in full lines.

We claim:

The ornamental design for a portable cable vulcanizer, as shown and described.
